UNITED STATES PATENT OFFICE.

CARL GIESECKE, OF BRUNSWICK, GERMANY.

APPARATUS FOR DRESSING THE ORES CONTAINING GOLD AND SILVER.

1,003,595.

Specification of Letters Patent. Patented Sept. 19, 1911.

Application filed May 12, 1910. Serial No. 560,880.

To all whom it may concern:

Be it known that I, CARL GIESECKE, citizen of the German Empire, residing at Brunswick, Germany, have invented new and useful Improvements in Apparatus for Dressing the Ores Containing Gold and Silver, of which the following is a specification.

My invention relates to winning noble metals, and a primary object is to provide an improved apparatus for dressing ores, particularly those containing gold and silver, according to the process forming the subject-matter of my co-pending application filed May 12, 1910, Serial No. 560,880.

One illustrative embodiment of my invention is represented by way of example in the accompanying drawing, wherein,

Figure 1 shows my apparatus in vertical section, Fig. 2 the same in end elevation, and Fig. 3 the same in plan; Fig. 4 is a section on the line X—X in Fig. 1, and Fig. 5 is a perspective view of the mixing device.

Referring to the drawing, the ore, which has been preliminarily worked up to pieces about 60 mm. in diameter in well-known manner on large stone breakers and similar machines, passes from the feed hopper 1 onto a rotating plate 2 which supplies it in uniform quantities to the inlet pipe 3 of the mill. This mill comprises three principal parts, namely, the two drum or tubular mill chambers 4 and 7 and a mixing apparatus 10.

In the chamber 4, which works with steel balls, the ore is preliminarily disintegrated to a degree of fineness which approximately corresponds to fine sand. The chambers 4 and 7 are separated from one another by a double wall 5, 6. The purpose of this double wall is to convey under specially favorable conditions the preliminarily disintegrated ore into the second grinding chamber 7 which likewise has steel balls. The wall 5 has its overflow orifices more at its outer periphery, while in the wall 6 only one or more orifices are provided in the center thereof. The material will thus issue from chamber 4 through the outer portion of wall 5 but pass from the center of wall 6 into chamber 7. The chamber 4 has a larger diameter than the chamber 7 which latter, however, is considerably longer than the former. Now in this chamber 7 the entire quantity of ore containing precious metal is

ground to a high degree of fineness. In order to obtain the desired degree of fine-

ness with relatively little power and in the shortest time, an admixture of water with the ore before the commencement of the grinding operation until its completion is 60 admissible only in the ratio of about 33½% as indicated above. Consequently, in the chamber 7 a thick slime of the very finest particles is produced containing approximately 33½% of water, which, in this condition would not be adapted to be conveyed, without special mechanical auxiliary means, into the lixiviation plant, or, lastly, onto amalgamating tables, because, in consequence of its small percentage of water, it is 70 lacking in the essential capability of flowing readily. Now in order that this finely ground ore may nevertheless possess this capability before it leaves the mill, it is subjected to another special treatment in the 75 apparatus 10 which is connected to the chamber 7. This apparatus 10 preferably has a larger diameter than the chamber 7 and preferably comprises a cylindrical drum whose central orifice is limited by a 80 collar-like portion 13; this apparatus is separated from the chamber 7 by a perforated wall 8, whose orifices 9 (Figs. 1, 4 and 5) with the aid of a funnel-shaped portion 11 form the limited connection between chamber 7 and drum 10. A water pipe 12, whose outlet may be formed, if desired, as a sprinkler, opens into the drum 10 and continuously supplies about 100-800% water to the thick slime which issues from the orifices 9 and is distributed by the part 11 onto the periphery of the drum. As the drum 10 rotates with the mill during this operation and the slime is held in the drum, the same is mixed intimately with water and 85 converted into a thin pulp. This pulp then flows through the part 13 into the channel 14 which conducts it to the lixiviation plant.

For increasing the mixing action in the 100 drum 10 ribs 16 or the like are arranged at certain intervals on the inner periphery of the drum (Fig. 4). Other auxiliary means, however, may be arranged for obtaining a mixing action.

I claim:

1. In apparatus for dressing the ores containing gold and silver, the combination, with a rotating ball grinding-drum of large diameter, of a second rotating ball grinding-drum of smaller diameter, said two drums being disposed in end to end relation, means

for the passage of material from said first-named drum into said second-named drum in such a manner that the material is discharged into the center only of the second-named drum, a rotating mixing device connected with the discharge end of the second drum, and means for supplying water to said mixing device.

2. In apparatus for dressing the ores containing gold and silver, the combination, of a mill comprising a rotating ball grinding-drum of large diameter, and a second rotating ball grinding-drum of smaller diameter, a double wall separating said two grinding drums, means for admitting material from said first-named drum into the space between said walls, means for discharging the material from between said walls into the center of said second-named drum, a rotating mixing device disposed against said second-named drum, means for discharging material from said second-named drum into said mixing device, and means for supplying water to said mixing device.

3. In apparatus for dressing the ores containing gold and silver, the combination of a mill comprising a rotating ball grinding-drum of large diameter and a second rotating ball grinding-drum of smaller diameter but longer than said first-named drum, a double wall arranged between said two drums, one of said walls being provided with a plurality of perforations and the other of said walls forming part of said second-named drum having a single perforation in the center thereof, so that material may be discharged from said first-named drum into the center of said second-named drum, a rotating mixing device connected with the discharge end of the second drum, and means for supplying water to said mixing device.

4. In apparatus for dressing the ores containing gold and silver, the combination of a mill comprising a rotating ball grinding-drum of large diameter and a second rotating ball grinding-drum of smaller diameter

but longer than said first-named drum, a double wall arranged between said two drums, one of said walls being provided with a plurality of perforations and the other of said walls forming part of said second-named drum having a single perforation in the center thereof, so that material may be discharged from said first-named drum into the center of said second-named drum, the opposite and discharge end of said second-named drum being provided with perforations, a mixing device having its wall disposed against said discharge end of said drum, said wall being provided with perforations which register with said first-named perforations, and means for supplying water to said mixing device.

5. In apparatus for dressing the ores containing gold and silver, the combination of a mill comprising a rotating ball grinding-drum of large diameter and a second rotating ball grinding-drum of smaller diameter but longer than said first-named drum, a double wall arranged between said two drums, one of said walls being provided with a plurality of perforations and the other of said walls forming part of said second-named drum having a single perforation in the center thereof, so that material may be discharged from said first-named drum into the center of said second-named drum, the opposite and discharge end of said second-named drum being provided with perforations, a mixing device having its wall disposed against said discharge end of said drum, said wall being provided with perforations which register with said first-named perforations, and means for supplying water to said mixing device.

In testimony whereof I have signed my name to this specification in the presence of two subscribing witnesses.

CARL GIESECKE.
